UNITED STATES PATENT OFFICE.

JOHN NICHOLAS WEBER, OF WAUKESHA, WISCONSIN.

APPARATUS FOR GIVING MUD BATHS.

Application filed July 19, 1926. Serial No. 123,435.

This invention relates to apparatus for giving mud baths.

In devices used heretofore for giving mud baths, it has been the common experience that the patients felt insecure in these devices due to their relatively frail construction, and further the patient was not comfortable in the mud baths, as the mud soon chilled either below or above his body, and further, his body was held in an uncomfortable position and the mud soon squeezed out from beneath the projecting portions of his body.

This invention is designed to overcome the above noted defects and objects of such invention are to provide a novel apparatus for giving mud baths, which is so constructed that it holds the body in a comfortable, semi-reclining position, and in such a manner that the mud does not squeeze out from beneath the body, and which further keeps all portions of the mud and body at the required temperature and supplies a constant flow of warmed, fresh air, evenly distributed, completely around the entire apparatus, so that there is no possibility of the patient becoming chilled, or of a cooling of the mud, or of a stagnant air condition.

Further objects are to provide an extremely rigid and secure construction, which gives the patient the impression of absolute security, which is sanitary, and is adapted and designed to be washed out quickly in the presence of the patient, so that the patient is assured of a clean tub or couch, and fresh mud, and in which the tub drains to the lower or foot end, so that no mud or sediment is left.

Further objects are to provide a novel form of mud bath apparatus in which a quick draining of the mud from the tub is assured, in which an auxiliary chamber is provided for the reception of the mud directly from the tub, so that it will receive the mud immediately and without delaying the use of the apparatus, and which will thereafter discharge the mud most slowly into the outlet or sewer pipe.

An embodiment of the invention is shown in the accompanying drawings in which:—

Figure 1 is a side elevation of the apparatus;

Figure 2 is a plan view thereof;

Figure 3 is a transverse sectional view on the line 3—3 of Figure 2;

Figure 4 is a vertical longitudinal sectional view on the line 4—4 of Figure 2;

Figure 5 is a sectional view on the line 5—5 of Figure 4.

Referring to the drawings, it will be seen that the apparatus consists of a tub 1, which has a gradually raised back or head portion 2, so that a curved, gradually upwardly slanting bottom portion 3 is provided, as shown most clearly in Figure 4. This bottom portion rounds at its side edges and gradually merges into the top portions of the apparatus. It is of general oval shape except that the foot is turned upwardly, as indicated at 4, and is rounded at its point of union with the bottom 3, and with the top, as shown in Figure 4. This entire apparatus is formed of moulded concrete or imitation marble or other material of this general nature, and is accurately contoured so as to give the utmost comfort to the patient, and to hold him in a semi-reclining position.

This body portion of the tub is carried by hollow tiles 5, as shown in Figure 4, and the outer face of the hollow tiles is finished in any appropriate and harmonizing manner, as by means of the regular tile face 6. It is to be noted that the interior of the support for the tub constitutes a rectangular hollow box. This box is divided by a partitioned wall 7, also preferably formed of hollow tile. Within the marginal portions of the tub, a plurality of short, downwardly curved pipes 8 are set and open outwardly through grating members of ornamental design, as indicated at 9 in Figures 1 and 4. The foot portion of the tub is provided with a plurality of horizontal pipes 10 which lie closely adjacent the undersurface of the tub bottom, and which open outwardly through the foot and through the grating members 9 located across the foot portion of the tub. These pipes, therefore, communicate with the interior or heating chamber 10' and conduct heated, fresh air outwardly through the sides and ends of the tub, so that a constant stream of warm, fresh air passes upwardly and around the patient and tub at all times.

The means for heating the air may consist of a radiator 11, located within the compartment 10'. Further, this compartment is supplied with air through the aperture 12 in the floor of the room, such aperture communicating with a primary heating chamber 110.

13. Within this primary heating chamber, a radiator 14 is provided for initially tempering or heating the air. This primary heating chamber is supplied with fresh air by means of a passageway or duct 15, leading to the outside of the building.

In order to prevent the hot air from rising and flowing primarily to the upper or head portion of the tub, a plurality of spaced baffles 16 are carried by the underside of the tub bottom 3, as shown in Figure 5. These baffles form sprockets for the heated air and interrupt its flow to the upper end of the tub and insure an even distribution of the heat throughout the body portion of the tub. In addition to this, as previously described, the pipes 10 insure the heating of the foot end of the tub, and also cooperate with the pipes 8 to secure an even distribution of fresh, heated air completely around all edges of the tub.

The means for draining the mud from the tub after it has been used, comprises a large rectangular discharge opening 17 which is closed by means of a wooden, fibre, or similar plate 18. This plate seats upon shoulders, and forms a continuation of the surface of the bottom of the tub, as shown in Figure 4. Below the opening 17, an auxiliary or initial receiving chamber 19 is provided for immediately receiving all of the mud washed downwardly from the tub. This chamber 19 communicates with the discharge pipe or sewer 20.

The construction just outlined, permits the washing of the mud downwardly, easily and in a very quick manner into the compartment 19, the compartment being of sufficient size to temporarily store the mud, and to allow it to more slowly discharge into the sewer or drain pipe, so that the operation of the apparatus is not delayed.

On the side of the tube, a water valve 21 (see Figure 1) is located and supplies a hose 22, which has a sprinkler 23 at its free end, such sprinkler being normally held within a clip 24, so that the hose is held parallel to the side walls of the tub.

The operation of the apparatus is as follows:

50 A patient is brought into the treatment room and stands adjacent the tub, while the operator removes the footboard or plate 18, and washes the mud downwardly by means of the hose and spray so that the patient actually sees the used mud quickly discharged from the tub, and the tub rinsed clean. Thereafter, the foot board is replaced and fresh mud is brought in at the required temperature. This is placed in the tub and the patient lies thereon. The patient is then covered with the mud and allowed to remain in the tub the requisite length of time. Upon his leaving, another patient is brought in and the cycle of operation is repeated. It is to be particularly noted that the auxiliary

chamber permits the quick washing and draining of the mud from the tub in the presence of the patient, the mud continuing to empty into the discharge pipe or sewer while the tub is in actual use.

Further, it is to be noted that the heating means is so arranged that the tub and mud are maintained at a constant temperature as required for the particular treatment, and in addition to this, that the patient is surrounded by a heated, continuous stream of fresh air, so that no possible chilling can occur.

Further than this, it will be seen that the apparatus presents a very pleasing appearance, and is of attractive design. None of the parts used in heating or draining the tub, with the exception of the sprinkling hose, are visible and, consequently, the utmost appeal is made to the patient while at the same time the utmost comfort and efficacy of treatment is secured.

Although the invention has been described in considerable detail, such description is intended as illustrative rather than limiting as the invention may be variously embodied and as the scope of such invention is to be determined as claimed.

I claim:

1. An apparatus for giving mud baths, comprising a tub formed of rock-like material and having a rounded elongated depression for the reception of the mud and the body of the patient, said depression having a large discharge opening, a plate for closing such opening, a compartment positioned below said opening, and a discharge pipe leading from such compartment.

2. An apparatus for giving mud baths, comprising a tub having a depression for the reception of the mud and the patient's body, and having an aperture communicating with such depression said aperture being relatively large, an auxiliary compartment for temporarily storing the mud discharged through such aperture, a discharge pipe communicating with the lower end of said auxiliary compartment, a plate for closing such aperture, and means for washing the mud from the tub through the aperture, whereby the mud may be quickly discharged from the tub and may be more slowly discharged from the auxiliary compartment.

3. An apparatus for giving mud baths, comprising a tub adapted to hold the patient in a semi-reclining position, a heating chamber located below said tub, heating means positioned within said chamber, means for leading fresh air into said chamber, and means for conducting the fresh air outwardly around the sides of the tub.

4. An apparatus for giving mud baths, comprising a tub, a supporting wall for carrying said tub, a partition dividing the compartment formed by the supporting wall

into a main compartment and an auxiliary compartment, means for supplying the main compartment with fresh air, heating means for heating the air, a plurality of pipes leading from said main compartment through said auxiliary compartment for conducting hot air adjacent the foot portion of the tub over the auxiliary compartment, said tub having passageways formed completely around its marginal portion for the discharge of the heated air in a distributed manner.

5. An apparatus for giving mud baths, comprising a tub having a body portion for holding the patient in a semi-reclining posi-

tion, said tub having a plurality of baffles extending downwardly from its bottom surface, heating means located below said baffles, and means for supplying fresh air to said heating means such fresh heated air rising 20 upwardly against the bottom of the tub and being distributed by the baffles, said tub having apertures around its marginal portion for the discharge of the heated air.

In testimony that I claim the foregoing I 25 have hereunto set my hand at Milwaukee, in the county of Milwaukee, and State of Wisconsin.

JOHN NICHOLAS WEBER.
